UNITED STATES PATENT OFFICE.

PETER J. VETLESEN, OF MINNEAPOLIS, MINNESOTA.

DESIGN FOR A WASHSTAND.

SPECIFICATION forming part of Design No. 31,096, dated June 27, 1899.

Application filed May 13, 1899. Serial No. 716,751. Term of patent 7 years.

To all whom it may concern:

Be it known that I, PETER J. VETLESEN, a citizen of the United States, residing at Minneapolis, in the county of Hennepin and State 5 of Minnesota, have invented and produced a certain new and useful Design for Washstands; and I do hereby declare the following to be a full, clear, and exact description of the invention, such as will enable others skilled in 10 the art to which it appertains to make and use the same.

This invention relates to certain new and useful improvements in designs for washstands; and it consists of the configuration 15 more fully hereinafter explained.

The accompanying facsimile or drawing illustrates a washstand embodying the features of the design.

The design consists of compound-curved 20 frame members 1, 2, and 3, of greater width apart at the bottom than at the top and connected to a top ring 4 and an intermediate ring 5, the bottoms of the members 1, 2, and 3 terminating in scroll-feet 6, projected in such 25 directions as to serve the purpose of base- rests. Between the said feet other scrolls 7 are located and also extend outwardly in opposite directions and assist in giving the entire device a stable support. The frame mem- 30 bers 1, 2, and 3 have a network 8, attached thereto at the rear, leaving the front side of

the device open, and secured to the said mem- bers at regular intervals are horizontal plates or rests 9, 10, 11, 12, and 13. These plates or base-rests are arranged in vertical aline- 35 ment and each has a surrounding scalloped guard 14 and are supported by scroll-brackets 15, extending inward from the frame mem- bers. The several plates, together with the rings 4 and 5, provide means for holding arti- 40 cles pertaining to a bedroom or lavatory serv- ice, and around the rear part of the upper ring 4 a guard 17 is attached and in the form of a conventional acanthus.

From the side members 1 and 2 of the frame 45 scrolls 18 project outwardly, and near the bottom of the design are opposite single acanthus-leaves 19.

The essential features of the design, how- 50 ever, reside in the frame members 1, 2, and 3, the rings 4 and 5, and the plates or supports 9, 10, 11, 12, and 13 of the form set forth.

Having thus described the invention, what is claimed as new is—

The design for a washstand herein shown 55 and described.

In testimony whereof I affix my signature in presence of two witnesses.

PETER J. VETLESEN.
